ELECTRICAL PICK-UP

Israel N. Steigman, Brooklyn, N. Y.

Application September 18, 1929, Serial No. 393,383

9 Claims. (Cl. 179—100.41)

This invention relates to electrical pickup apparatus designed to convert stimuli, such as sounds, movements, or mechanical vibrations into such pulsating electric current as may be later broadcast, reproduced or recorded, and which correspond without material distortion to the original sounds, movements or vibrations. Such apparatus usually comprises a dynamo or generator including a magnet for generating a magnetic field, an armature movable in the field under the impulse of a stimulus, and coils in which current is generated on the movement of the armature.

As a particular application of my invention, my improved apparatus may be used to change the mechanical vibrations of a stylus operating in the groove of a phonograph record, into equivalent electrical impulses, or my apparatus may be used as a microphone, as desired. The electrical output of the apparatus may later be amplified, as for instance, by means of well-known thermionic amplifiers, and made to operate loud speakers or recording instruments, such as phonographs, telephones or the like, or it may be used directly to modulate high frequency circuits for broadcasting purposes.

The vibrations or movements of the armature portion of apparatus of the type to which this invention pertains, have heretofore been more or less mechanically restrained by resilient damping means, such as for example, springs, interposed rubber members, cloth, or the like. Such damping means not only causes material loss of the effective power of the stimulus operating the apparatus, which power, it is understood, is extremely minute in the first instance, but the damping means has the additional defect of so restraining the free vibration of the armature as to cause undesirable and often, gross distortion of the reproduction, resulting in lack of correspondence of the output with the stimulus.

Distortion of reproduction in previously known apparatus of this type also occurs owing to the fact that vibrations at a certain frequency, corresponding to the natural frequency of vibration of the damping means, can be imparted to the armature more easily than other frequencies, which other frequencies are therefore transmitted with greater difficulty and are more or less repressed, preventing faithful reproduction, and resulting in further diminution of the effective power of the stimulus. Furthermore, pickup apparatus heretofore in use has been not only mechanically restrained by the damping means referred to above, but the armatures thereof have been of

excessive weight, due to the loading thereof with coils and other devices. The additional weight is enough to resist the free vibration of the armature under the impulse of the stimulus and is further, enough to cause undesirable wear of the parts and of the stimulus where for example, phonograph records are used as the transmitting medium. Finally, such weighted armatures are subject to the defect that considerable energy in transmission is lost and consequent distortion occurs due to the inertia of the comparatively heavy armature, and the consequent difficulty of starting and stopping the movement thereof.

Some means have therefore been employed customarily to correct the distortion caused by the above mentioned defects. Said means has usually taken the form of electrical or wave filters for eliminating or altering the undesirable portions of the electrical reproduced impulses or waves, but such filters result in further undesirable absorption of energy, and are an expensive and inefficient means for approximating the desired result.

My invention contemplates the provision of a simple device to govern the extent of the pulsations of the electrical output of a pickup without the necessity for the use of wave filters, said device consisting merely of the control and adjustment of the predetermined area of the contiguous armature and pole faces.

My invention further contemplates the provision of means for so mounting and vibrating the armature of the pickup that the faces of said armature vibrate in a plane substantially at right angles to the magnetic lines of force, and so that said armature is entirely free of mechanical restraint against vibration other than that due to its own weight, and from which springs and damping means are entirely eliminated, the armature nevertheless being maintained in its proper position in the magnetic field. My invention further contemplates the provision of an armature of minimum weight whereby the inertia thereof against free vibration is reduced to a minimum, with consequent maximum efficiency in faithful reproduction and with maximum utilization of the energy of the stimulus put thereon, so that an extremely high degree of perfection of reproduction may be attained without the necessity for the use of wave filters. My invention further contemplates the production of a simple and comparatively inexpensive and efficient apparatus for the reproduction, broadcasting or recording of the stimulus applied thereto, and which

may also be operated as a microphone, if desired.

The various objects of my invention will be clear from the description which follows, and from the drawing, in which,

Fig. 1 is a perspective view of the preferred form of my improved pickup, showing the device in use for the electrical conversion of sound in connection with a phonograph record.

Fig. 2 is a similar view of one of the magnet poles and of a portion of the armature therefor, showing a modified form of the pole and armature faces, the areas of which govern the degree of reluctance in the magnetic circuit, and therethrough govern the extent and characteristics of the pulsations of the electrical output.

Fig. 3 is a diagrammatic view of my improved apparatus, showing the magnetic circuit therefor and showing, further, the connection thereof to a suitable amplifier means such as a thermionic transformer.

Fig. 4 is a perspective view of a modified form of my apparatus illustrating a modified arrangement of the magnet poles and armature.

Fig. 5 is a similar view of the same, showing another modified arrangement.

Fig. 6 is a similar view of the same, showing a modified form of armature and showing the connection thereof to a suitable sound responsive means whereby the apparatus may be used as a microphone, and

Fig. 7 is a similar view of another modified form of my apparatus, showing a different form of the faces of the pole pieces and armature.

Figure 8 shows a modified form of my device in which the armature pivot is mounted above the airgap.

In that practical embodiment of my invention which I have illustrated by way of example, in Fig. 1, a suitable magnet 10, which is preferably a permanent magnet, is provided with a pair of poles 11 and 12 which may be disposed in various positions, as is shown in the remaining figures, and as will be more fully explained hereinafter. The magnet 10 may be secured or held in proper stationary position by means of a suitable extension 13 thereon, as may be found convenient or desirable.

Wound about the poles 11 and 12 and preferably spaced somewhat from the preferably plane terminal faces 14 and 15 respectively thereof are the coils 16 and 17 respectively, each composed of a number of turns of fine insulated wire. The movable or vibratory member of my improved pickup comprises the armature, preferably made of a piece of magnetic material such as soft iron, and made as small as may be convenient. As illustrated in Fig. 1, the armature is arranged opposite the pole faces 14 and 15. Said faces 14 and 15, as well as the operative faces 19 and 20 of the armature may be of any desired polygonal or other form presenting two or more operative facets to the magnetic field induced by the magnet 10. As illustrated, two facets 21 and 22 are provided on the pole face as 14 and two similar facets 25 and 26 are provided on the armature face 19, though it will be understood that any desired number of facets disposed on planes angularly arranged may be used instead, as will be obvious to those skilled in the art and hence which need not be shown.

I prefer, however, that a single groove only be made in each of the armature and pole faces, and that said groove be rectangular in cross-section, though I do not desire to be understood as limiting myself to a single groove of any definite shape,

as above explained. As illustrated in Fig. 1, the width of the armature 18 is very little less than the distance between the faces 14 and 15 of the adjacent poles, whereby the armature is arranged with the faces 19 and 20 thereof as close as is physically possible to the respective pole faces 14 and 15. I prefer to so mount the armature that the gap between the armature faces and the pole faces, while being of minimum extent, is permanent as regards its width, and invariable for all practical purposes.

I further prefer to so mount the armature 18 that the faces 19 and 20 thereof move in a path parallel to and across the pole faces 14 and 15 and at a fixed distance therefrom, and are constrained to move in the path described substantially without mechanical restraint against vibration in said path. Toward this end, the armature is pivoted about a suitable axis.

As shown in Fig. 1, I prefer to provide a non-magnetic shaft as 29 passing through part of the armature and spaced from the poles 11 and 12 and terminating in conical bearings 30 mounted in suitable supports as 31 secured to the magnet 10. A stylus as 32 may be secured to the armature 18 on the opposite side of the pivot shaft 29 from that on which said poles are arranged, though it will be understood that the stylus may be on the same side of the shaft as are the poles, if desired. Said stylus may be held to the armature by means of a chuck 33 secured by a suitable adjusting screw as 34. The stylus 32 is intended to be inserted into the undulated track or groove 35 of the phonograph record 36, whereby rotation of the record in the usual manner causes the stylus 32 to oscillate about the pivot shaft 29 under the impulse of the variations in said track and thereby causes the armature faces to vibrate correspondingly, across and parallel to the pole faces.

No coils are provided on the armature so that the groove 35 has only a minimum amount of weight to move and the armature is free from restraint against vibration except that occasioned by the inertia due to its own weight. This inertia, it will be seen, is also reduced to a minimum by reason of the simplicity of the armature and the possibility of reducing its weight to a minimum. Stops as 37 of non-magnetic material may be provided for limiting the vibratory movement of said armature, said stops preferably projecting from the magnet 10 and being so spaced apart as to maintain the armature 18 at all times in the magnetic field of the poles 11 and 12.

Should the armature therefore be subjected to an unusual force tending to throw it completely out of the magnet field, the stops 37 nevertheless maintain the armature within the range of the magnetic force, which is sufficient to pull the armature back into its proper position without the necessity for using mechanical means such as springs or the like. In other words, the magnetic force in the field is the agent serving to maintain the armature in its operative position without other aid.

The coils 16 and 17 are suitably interconnected as by means of the conductor 38 (Fig. 3), the terminal wires 39 and 40 of said conductor being connected to suitable amplifying apparatus 41, as will be seen from Fig. 3.

The magnetic reluctance of the magnetic circuit may be varied by changing the position of the armature in the magnetic field of the poles, by movement of the armature across and substantially parallel to the pole faces and not from

pole to pole. By so varying the magnetic reluctance, a current varying in intensity and frequency in exact correspondence to the vibration of the armature, is induced in the coils 16 and 17 and may be used for the purposes heretofore mentioned.

As illustrated in Fig. 4, the armature 42 is arranged across the ends of the magnet poles 43 and 44, the respective pole faces 45 and 46 of which are arranged in the same plane. The pivoting shaft 47 for the armature may be similar to the shaft 29, but only one face as 48 of the armature is operative in this modification.

As shown in Fig. 5, the pole faces 49 and 50 of the magnet 10 are arranged at substantially right angles to each other so that the surfaces 51 and 52 of the armature 53 are correspondingly arranged although the operation thereof, as above described, is not materially altered.

20 As illustrated in Fig. 6, the armature 54 may be connected to the cone 55 or other suitable diaphragm by means of the connecting member 56, said cone or diaphragm being vibratory under the impulse of sound waves.

25 The pole faces of the magnet 10 illustrated in Fig. 6 are shown substantially identical with those shown in Fig. 4 and therefore need not be further described. The armature 54, however, may be pivoted on a shaft as 57 arranged parallel 30 to the pole faces 45 and 46. The vibration of the armature across the pole faces without changing the width of the gap may be made to occur, however, in substantially the same way irrespective of the arrangement of the pivot therefor.

35 In Fig. 7, I have shown another form of mounting whereby the armature 58 may vibrate without change in the width of the gap. In this case, the axis of the pivot shaft 59 lies in a plane perpendicular to the plane of the magnet 10, in 40 distinction from the arrangements of the pivot shafts 29, 47 and 57, the axes of which lie in planes parallel to the plane of the magnet. This arrangement of the pivot shaft 59 necessitates the arrangement of the pole faces 60 and 61 and 45 also of the armature 62 and 63 in cylindrical surfaces centering about the axis of the pivot shaft so that the gap may remain unchanged in thickness during vibration of the armature 58. The grooves in the pole and armature faces have 50 also been shown as triangular instead of rectangular as in the other modifications.

Means may be provided for predetermining the characteristic of the current induced in the coils 16 and 17 on predetermined motion of any of the 55 armatures 18, 42, 53, 54 and 58 across their pole faces.

Said means may take the form of a multiplicity of facets as 21, 22, 25 and 26 formed by making one or more grooves as 23 and 24 in the pole 60 faces and armature faces respectively. As illustrated in Fig. 2, I prefer that said means take the form of a variation in the shape of the periphery and extent of the areas of the pole facets 64 and 65 and of the armature facets 66 and 67. 65 The variation in said areas may be effected by changing the shape of the sides of the grooves 68 and 69 made in the magnet pole faces and in the armature faces, respectively, and consequently, in a change of the shapes of the sides 70 and 71 of the pole facets and of the sides 72 and 73 of the armature facets.

In other words, a variable change of area of the effective armature and pole surfaces may result on movement of the armature through a predetermined angle in different positions of the

armature. If there were no grooves in the armature and pole faces, and the width of the pole faces were greater than the maximum amplitude of vibration of the armature, no current would be induced in the coils. If the sides 80 of the grooves were vertical, then there would be a uniform variation in the current induced in the coils 3 during a single movement of the armature in one direction, but if the sides of the groove were straight but inclined at an angle other than a right angle to the upper and lower faces of the poles, then the variation is uniformly variable.

Again, if the sides of the groove were curved along predetermined lines, then the variation would be variably variable and may be predetermined to produce an output of the desired characteristic, as should be clear to those skilled in the art. For example, the curves of the groove sides may be so designed that if the armature were to swing through an angle of two degrees and during that swing, to generate one volt, a swing of four degrees in the same direction might be caused to induce one and one-half or five or and other number of volts, and not two volts, and a swing of six degrees might be caused to 90 generate one and three-quarter volts or any other number of volts. The form of the sides of the grooves may be so designed that during a large swing of the armature, more current of greater voltage would be induced in proportion, in the 95 coils than during a small swing, or vice versa.

It will be seen, in any case, that the characteristic of the induced current is dependent entirely upon the effective areas of the adjacent pole faces and armature faces and that said areas may 100 be varied as desired. As shown in Fig. 7, the grooves 74 and 75 are made triangular instead of rectangular, the grooves in all cases being preferably deep enough to prevent any undesired passage of flux. As shown in Fig. 8, a multiplicity of grooves and a consequent multiplicity of facets are provided on the pole faces. The pivot 80 for the armature 81 is further arranged above the poles instead of below the poles as in Fig. 1 to give a somewhat greater leverage.

105 It will also be seen that by providing an armature free of coils and vibrating said armature so that the armature faces travel in a plane substantially parallel to the faces of the poles or in a cylindrical surface concentric with the pole faces, 110 I have produced a simple and efficient mechanism operating with a minimum waste of energy and accurately responsive to the stimulus applied thereto, whereby efficient reproduction with a minimum of distortion becomes possible.

115 It will further be understood that while I prefer to so pivot the armature that it moves as above described, the armature may also be pivoted so as to move at right angles to the described direction or across the poles from top to bottom, if desired, by merely changing the relative position of the pivot on the armature. It will further be understood that while I have shown a record having a groove of one type, any type of grooved record may be used as a stimulus to the apparatus 120 and that by means of a suitable diaphragm responsive to vibrations, my improved apparatus may be used as a microphone, if desired.

125 While I have shown and described a preferred embodiment of my invention, it will be understood, further, that I do not wish to limit myself thereto but intend to claim my invention as broadly as may be permitted by the state of the prior art and the terms of the appended claims.

130 I claim:

150

1. In an electrical pick-up, a magnet having poles thereon, relatively stationary coils on the poles, a movable soft iron armature free of coils and having multi-faceted faces thereon cooperating with the pole faces for varying the reluctance in the magnetic circuit of the magnet in a variably variable predetermined manner, and means for pivotally supporting the armature so that the faces of the armature remain at a predetermined distance from the pole faces during the vibration of the armature in response to a stimulus, said means and the stimulus being the only mechanical forces other than said magnet acting upon the armature to cause movement of the armature free from damping and lag effects. 80
2. In an electrical pickup device, the combination with pole faces of a magnet of vibratory soft iron armature free of coils and having faces terminating in at least one edge curved in the direction of its length cooperating with the pole faces and adapted to vary the reluctance in the magnetic circuit of the magnet in a predetermined manner independent of the variation induced by the stimulus, and means for pivotally supporting the armature so that the faces of the armature move in a surface parallel to the pole faces. 85
3. In an electrical pickup device, the combination with a pivoted armature, of magnet poles serving as the sole means acting upon the armature to swing it about its pivot into position to maintain it in the magnetic field of the poles, and means for pivotally supporting the armature for vibration across the lines of force of the field and spaced from the poles to transmit to the armature substantially the full force exerted by a stimulus thereon, and a stylus carried directly by the armature. 90
4. In an electrical pickup device, the combination with a pivoted armature, of magnet poles serving as the sole means acting upon the armature to swing it about its pivot into position to maintain it in the magnetic field of the poles, means for supporting the armature for vibration across the lines of force of the field and out of contact with the poles, in response to a stimulus, and means for preventing the vibratory movement of the armature beyond predetermined limits. 95
5. In an electrical pickup device, the combination with means for inducing a magnetic field, means responsive to variations in the magnetic reluctance of the circuit for producing current, and means for varying the reluctance of the circuit mounted for movement across the lines of force of said field and normally maintained in said field solely by said first-mentioned means to utilize substantially the full force of a stimulus applied thereto, said reluctance varying means including a pivoted armature provided with a series of spaced faces lying in the same warped surface, each of said faces having at least one longitudinal edge thereof in the shape of a curve of predetermined shape. 100
6. In an electrical pickup device, a magnet, grooved magnet poles thereon, coils on said poles adapted to have current induced therein on the variation of the magnetic reluctance in the field of said magnet, an armature having grooved faces therein arranged at a predetermined fixed distance from the faces of said poles, said armature being pivoted to maintain said distance constant, the effective area of the grooved pole faces and the armature faces being predetermined by shaping the peripheral edges of said faces to control the characteristic of the current induced in said coils. 105
7. In an electrical pick-up device adapted to be actuated by a revoluble phonograph record, a magnet having a pair of poles thereon, each of said poles having a reentrant recess to interrupt the faces of said poles, the longitudinal edges of said recess being of predetermined curvilinear shape so that the pole surfaces beyond the recess are of variable widths throughout their lengths, a coil wound about each pole in spaced relation to the recess therein, a pivoted armature, a stylus adapted to engage the record carried by the armature, means for pivotally supporting the armature so that each face of the armature is maintained a constant distance from the adjacent pole face, the armature faces having recesses corresponding to and similar to the recesses of the pole faces. 110
8. In an electrical pick-up device, a magnet, a pair of pole pieces extending from the sides of the magnet toward each other and spaced apart, an armature arranged in the space between said pole pieces, the inner end of each of said pole pieces having a re-entrant groove therein, and the faces of the armature adjacent the pole faces having a similar groove therein and substantially the same shape and size as that of the corresponding groove in the adjacent pole face, means for pivotally supporting the armature for movement across the pole faces while maintaining the distance between the pole faces and the armature faces constant, a vibratory member adapted to have a stimulus applied directly thereto carried by the armature, and a coil wound about each of the pole pieces and connected to each other and arranged in spaced relation to the grooves of said pole pieces. 115
9. In an electrical pick-up device, a U-shaped magnet, pole pieces extending toward each other from the sides of the magnet and spaced from the ends thereof, a coil wound about each of the pole pieces, an armature arranged for vibratory movement between the pole pieces, a pivot for the armature extending between and supported by the sides of the magnet, and a stylus carried by the armature below the pivot, said pivot maintaining constant the spaces between the armature faces and the faces of the pole pieces. 120
